CLAIM

The ornamental design for a cordless electric blower, as shown and described.

DESCRIPTION

FIG. 1 is a left side elevational view of a cordless electric blower showing the design;

FIG. 2 is a right side elevational view thereof;

FIG. 3 is a top plan view thereof;

FIG. 4 is a bottom plan view thereof;

FIG. 5 is a rear elevational view thereof;

FIG. 6 is a front elevational view thereof; and,

FIG. 7 is a right side perspective view thereof.

The air nozzle indicated by broken lines is for illustrative purposes only and forms no part of the claimed design.
